United States Patent Office

Des. 234,132
Patented Jan. 21, 1975

234,132

CIRCULAR BUILDING

Kenneth K. Varian, 6342 Orchardview Drive SE,
East Canton, Ohio 44730

Filed June 29, 1973, Ser. No. 375,063

Term of patent 14 years

Int. Cl. D25—03

U.S. Cl. D13—1 E

FIG. 1

FIG. 2

FIG.3

FIG.4

FIG. 1 is a perspective view of the entrance portion of the building showing my new design;

FIG. 2 is a top plan view thereof;

FIG. 3 is a side elevation looking in the direction of arrows 3—3, FIG. 2; and

FIG. 4 is a rear elevation looking in the direction of arrows 4—4, FIG. 2.

I claim:

The ornamental design for a circular building, as shown.
